ALEXANDER PALMROS, OF SYRACUSE, NEW YORK, ASSIGNOR TO THE PNEUMELECTRIC MACHINE COMPANY, OF SYRACUSE, NEW YORK, A CORPORATION OF NEW YORK.

FLUID-PRESSURE-DRIVEN TOOL.

1,072,358.

Specification of Letters Patent.

Patented Sept. 2, 1913.

Application filed November 25, 1905. Serial No. 289,127.

To all whom it may concern:

Be it known that I, ALEXANDER PALMROS, a citizen of Finland, and resident of Syracuse, in the county of Onondaga, State of New York, have invented certain new and useful Improvements in Fluid-Pressure-Driven Tools, of which the following is a specification.

This invention relates to fluid pressure driven tools such as mining machines, drills, hammers, riveting machines, ore stamps, dental instruments and the like, and it has for an object to improve that type of fluid pressure driven tools in which the pressure is developed within the tool.

In Letters Patent No. 761,602, granted May 31, 1904, to Carson W. Damron and myself, a machine is disclosed wherein a fluid pressure medium, kept supplied by a motor-driven pump, is compressed by the retracting stroke of the tool and permitted to expand and drive the tool forward, in developing the working stroke of the machine; while in an application filed by me on December 13, 1904, (Serial No. 236,738) the above principle is carried forward and applied with greater effect and economy by utilizing the tool piston to maintain the air supply, but only during a portion of its stroke, when the retarding influence due to pumping is immaterial, and by so combining a special type of prime mover that not only is the pump driven by the motor, but, the tool piston, being constantly connected, receives the driving force of the motor in addition to the force of the pressure medium, and the final impact is measured, not merely by the rate of forward movement developed by these combined driving forces, but by the product of this velocity by the combined mass of the driven member and the constantly connected (moving) driving member acting as a fly wheel. It is true that the fly wheel effect is not transmitted directly to the drill, but indirectly through piston connection which yields slightly at the instant of first impact, to relieve the shock on the machine, but the construction is such that the body of air through which this reinforcing blow is exerted is kept supplied in a dense condition and the effect is therefore peculiarly advantageous for the excavation

of many materials, where a prolonged crushing blow is most effective. That is to say, while there is a slight yield at first, the blow is followed up by the additional force before the material attacked can recover from the first load imposed upon it and the penetration is greater than results from a construction where the first shock is transmitted to and tends to arrest the entire train of driving parts.

In my present application, I still maintain the features of having the tool free to move forward with the suddenness due to the expansion of the air; of having each compression stroke start with a fresh charge of air, of adding the driving force of the motor to the expansion of the air in developing the speed of the tool; of building up or adding to the work stored in the tool to be used up at the time of impact; and following up the tool piston by the driving member to insure a full length stroke. But in the present case the driving member is a second piston constantly connected to the armature of the electric motor, retracting the first piston by suction or an equivalent means, compressing a charge of driving air by its retracting stroke, releasing the charge of air thus compressed, directly against the driven tool-piston, continuing the retracting stroke, after the charge of compressed air has been thus released in order to add the driving motor's force (acting through the body of air) to the expansive force, in the forward stroke, and raise the effectiveness of the compressed charge, reversing the driving piston and following up the driven piston and thus insuring full stroke of the latter and completing the work of the tool and sucking in a new charge behind the driving piston preparatory to repeating the cycle of movements. In other words, for accomplishing the results set forth above, I now provide a pair of suitably housed pistons, one of which is connected to the tool carrying member, and the other to a driving motor and connection between the pistons, whereby one piston may impart movement to the other during both the retracting and the percussion strokes of the tool, together with means for compressing a fluid on the retracting stroke of the tool and uti-

lizing said compressed fluid expansively, to impart movement to the tool during the percussion stroke of the latter, during which time the driven piston is also acted on by the driving piston, through the intermediate column of air. This intermediate column of air, being under compression, continues to transmit the driving influence of the one piston to the other, notwithstanding the acceleration of the driven piston relatively to the driving piston. The body of air through which the one piston reinforces the percussion stroke of the other is, in the embodiment herein disclosed, the same body of air that is compressed by the retracting stroke and acts upon the tool piston expansively.

Other and further objects will appear in the following description and will be more particularly pointed out in the appended claims.

In the drawings: Figure 1 is a vertical section of one embodiment of my invention; Fig. 2 is a horizontal section through the reducing gear connecting the motor with the driving piston; Fig. 3 is a detail section of the cylinder and its pistons, of another embodiment of my invention, showing mechanical means in addition to the vacuum producing means for holding the pistons together during their retraction; and automatically releasing the pistons at the end of such retraction; Fig. 4 is a view of an embodiment similar to Fig. 3 showing fluid operated means for releasing the mechanical retracting means; Fig. 5 is another embodiment in which the vacuum retraction is assisted by an electro-magnet; Fig. 6 is still another embodiment in which the retraction is assisted by fluid pressure; and Fig. 7 is a side elevation of a mining machine employing the embodiment of my invention shown in Fig. 6; Fig. 8 is a vertical section of a machine employing the embodiment shown in Fig. 4. Fig. 9 is a section through the valve at right angles to the section shown in Fig. 6.

While I have herein shown and described my invention as embodied in a mining machine, it is to be understood that this is for the purpose of illustration only and that the invention may be embodied in any machine to which it may be applicable.

Referring more particularly to the drawings, 1 indicates a common cylinder, to be hereinafter more fully described in which is mounted a pair of axially aligned independently movable pistons 2 and 3. The piston 2, which I shall term the "compression driving piston" is actuated by an electric or other motor 4 mounted upon the frame of the machine and connected with the pitman 5 of the driving piston preferably by means of a reducing gear.

65 The reducing gear, which I prefer to use,

comprises a small pinion 6 mounted on the shaft of the motor and meshing with a large gear 7 mounted upon a spindle 8 transverse to the pitman 5 and extending vertically in the rear of the motor into a bearing 9 on the frame of the machine. The large gear 7 transmits motion received from the pinion 6, to an eccentric pin 10 and in order to convert the throw of this eccentric pin into a right line movement coincident with the axis of the pitman, said pin carries a crank pinion 11, having a wrist pin 12 which connects with a cross-head 13^a on the pitman. The throw of the wrist pin 12, due to the rotation of the pinion 11, is exactly half the stroke to be imparted to the cross-head 5^a, while said pinion 11, by meshing with a fixed circular rack 13, receives one rotation about its center for each revolution of its center with the main gear 7.

The fluid driven or working piston 3 actuates the tool rod 15 which may either be connected to the piston as shown in Fig. 1, or separate therefrom as is common in other types of fluid pressure driven tools. The common cylinder 1, in which the driving and the driven or stroke pistons work, forms means for storing fluid on the rear or compression face of the driving piston during the pressure developing or retracting stroke, that is, during the simultaneous movement of the pistons or their movement in the same direction, this storage portion or compression space of the cylinder being located at one end thereof. A by-pass 16 extends from a point at or near the end of the cylinder to a point some distance from said end. This by-pass serves as a means of communication for admitting the fluid compressed during the retracting stroke from the rear or compression face of the piston 2 to the rear or controlling face of the stroke or working piston 3 or, in other words between the pistons 2 and 3, when the said piston 2 is located between the two ends of the by-pass. The admission of fluid under pressure between the pistons 2 and 3 causes the fluid to exert its expansive force against the piston 3 and gives to said piston its working or percussion stroke so as to project the tool rod 15. The fluid should be admitted between the pistons prior to the completion of the compression or retracting stroke of the driving piston, the by-pass being, for this purpose, so located as to be uncovered by the driving piston before it reaches the end of the compression or rearward stroke, and the ends of the by-pass being spaced apart to permit the piston 2 to have a movement between them. The object of this is to have the compression or driving piston continue to compress air after the driven piston commences its forward stroke, thus keeping the expanding air to a higher degree of efficiency than if the air were allowed to ex-

pand in the cylinder only at the end of the stroke.

Means is provided to permit the escape of fluid from the front of the driven piston after driving pressure has been imparted to the rear of said driving piston, this means being in the form of normally open ports 17 which are located a short distance from the opposite end of the common cylinder providing between the ports and this end of the cylinder, a cushion space 18. By the time the blow has been struck or the driven piston 3 reaches the cushioned end of the cylinder, the driving piston starts on its other or forward stroke. To admit a fluid to the storage end of the cylinder during the forward stroke to take the place of the fluid discharged through the by-pass 16, there is provided an inwardly opening valve 19 at said storage end of the cylinder through which valve the fluid is drawn by the vacuum created by the said forward movement of the driven piston. The air, between the opposed faces of the pistons, is expelled during such forward movement through an outwardly opening valve 20 located near the cushion end of the cylinder. Should the driven piston not go to the limit of its movement, a cushion will be formed between the two pistons, thereby preventing the pistons coming together and breaking any parts of the machine, and this cushion will assist in completing the stroke of the driven piston.

When the motor actuated piston 2 has been moved close to the stroke piston 3, a connection is established between the pistons to cause the pistons to move simultaneously or in the same direction during the retracting stroke of the driving piston 2; said connection permitting independent movement during the working stroke. This is accomplished in Fig. 1 solely by the formation of a vacuum between the pistons, or in other words, the displacing of the fluid in advance of the piston 3, due to the inward movement of the driving piston.

In the embodiment shown in Fig. 3, the operation of all the parts is the same and in addition thereto a mechanical means is provided for making positive the simultaneous movement of the pistons in the direction of retraction. For this purpose, the driven piston carries a pair of pivoted spring-pressed dogs 21 adapted to engage a shouldered projection 22 on the driving piston. When the driving piston reaches the end of its forward stroke, the dogs, riding on the tapered end of the projection, engage the shoulder on the same, and during the retracting stroke, the driven piston is simultaneously drawn in the same direction. To release these dogs at or near the end of the retracting stroke, a pair of sliding pins 23 is mounted in the driving piston and projects from both faces thereof, one end of each pin being

adapted to engage a nose 24 on one of the dogs, while the other end of each pin is adapted to engage the head of the cylinder. Thus, as soon as the pins engage the head of the cylinder, the dogs 21 will be moved on their pivots and out of engagement with the shouldered projection 22, and, at the same time, compressed air will be admitted between the opposed faces of the aligned pistons through by-pass 16.

In the embodiment shown in Fig. 4, there is provided a fluid operated means for releasing the mechanical holding means, at the end of retracting movement, to permit independent movement of the pistons. In this embodiment the shouldered projection 22, together with the spring pressed dogs 23 and their noses 24, is provided, as in Fig. 3. A sliding cup 25, mounted on piston 3 and surrounding the dogs 23, has a central perforation to permit the projection 22 to enter and become engaged by the dogs 23 at the end of the inward stroke. The inner edge of this cup engages the noses 24 on the dogs, and, when fluid is admitted between the pistons, near the end of the retracting stroke, the cup, moving under the influence of the fluid, moves the dogs on their pivots and the working piston 3 is projected.

In the embodiment shown in Fig. 5, the driving piston 3 carries an electro-magnet 26 which is connected by conductors 27 with contact plates 28 on the pitman 5. Sliding on the contact plates is a pair of contacts which cause a circuit to be established and a current to pass through the electro-magnet 26 during the retraction of the driving piston, the magnet thereby acting on the driven piston 3 and assisting the vacuum to cause the driven piston 3 to move with the driving piston 2, the circuit being broken at the end of said retraction to permit the fluid in the storage portion of the cylinder 1 to pass between the opposed faces of the piston by means of a by-pass 16 thereby projecting the driven piston 3.

In the embodiment shown in Figs. 6 and 7, the retraction of the driven piston is caused by fluid under compression and during the retracting stroke of the driving piston. The driven piston 3 is projected in the manner set forth with relation to the other embodiments. The opposite end of the cylinder has provided three ports 30, 31 and 32 which open into a valve housing 33 in which works a sliding valve 34 both faces of which are open to one another through channel 33a. This sliding valve is provided with a channel 35 which, in one position of the valve, connects the port 31 with a port 36 opening into the atmosphere and closed by a strainer 42, the valve taking this position at the commencement of the projection of the driven piston 3. After the driven piston 3 has been projected and the driving piston 2 starts on

its forward movement, the valve 34 shifts so as to uncover the port 30 and admit the air from between the pistons into the valve housing. When the driving piston has 5 reached the end of its forward movement and has started to return, the valve is again shifted to connect the port 32 with the valve housing, whereby fluid, stored in the valve housing during the forward stroke of the 10 driving piston 21, is admitted to the outer face of the driven piston 3 to assist vacuum in the retracting of the said piston. These several movements of the valve are produced by a cam 37 on the spindle 8 upon which the 15 large gear 7 is mounted. The cam 37 transmits this motion to the valve by means of a sliding bar 38 pivoted to one end of a rocking lever 39, the other end of said lever being connected by link 40 with the pitman 41 20 of the valve 34.

Having thus described my invention, what I claim and desire to secure by Letters Patent, is:

1. The combination with a suitably housed 25 driving piston, a suitably housed driven piston, means causing the pistons to move in the same direction at one time and means storing an expansible fluid under compression upon the movement of the pistons in the 30 same direction and admitting said compressed fluid to drive the driven piston in the other direction.

2. The combination of a suitably housed 35 compression-driving piston and a suitably housed driven piston, means causing the driven piston to be retracted during the compression stroke of the driving piston, and means providing communication between the controlling face of the driven piston and the 40 compression space of the driving piston, through which, a medium compressed during such retraction, is communicated to the driven piston.

3. In a percussion implement, a suitably 45 actuated fluid compressing piston, a fluid pressure driven piston, suitable housing for said pistons, said housing provided with means through which the fluid compressing piston displaces the fluid medium in rear of 50 the fluid pressure driven piston and causes the latter to be retracted during the compression stroke of the fluid compressing piston, and also provided with means providing communication between the controlling 55 face of the fluid pressure driven piston and the compression space of the fluid compressing piston through which the fluid medium compressed during such retraction, is delivered to the fluid pressure driven piston.

4. The combination with a motor actuated 60 driving piston, of a cylinder in which the said piston operates to compress a fluid medium provided with a by-pass at one end permitting the fluid compressed by said piston to pass to the opposite side of said driv-

ing piston when it is between the ends of the by-pass, and a suitably housed independent driven piston moved by the compressed fluid passing from the by-pass.

5. The combination with suitably housed 70 driving and driven pistons, means providing communication between one face of the driven piston and both the compression and opposite faces of the driving piston through which fluid may flow alternately between 75 the driving and the driven piston, the communication between the driven piston and the compression face of the driving piston being controlled by said driving piston, and comprising a by-pass, uncovered by the driving piston on its compression stroke.

6. In a percussion implement, a fluid compressing piston, a fluid pressure driven piston, suitable housing for said pistons, and means providing communication between 85 one face of the fluid pressure driven piston and both faces of the fluid compressing piston, said means in coöperation with the action of said fluid compressing piston being adapted to exert upon the fluid pressure 90 driven piston retracting influence and driving pressure alternately, and auxiliary means causing both pistons to move in the same direction during the retracting stroke.

7. In combination with suitably housed 95 driving and driven pistons, means providing communication between one face of the driven piston and both the compression and opposite faces of the driving piston through which fluid may flow whereby pressure 100 variations are alternately communicated from the driving to the driven piston, the communication between the driven piston and the compression face of the driving piston being controlled by said driving piston, said means of communication between the driven piston and the compression space comprising a by-pass, uncovered by the driving piston on its compressing stroke and located to be uncovered before the driving 110 piston reaches the end of its stroke, so that it continues to supply pressure medium during a portion of the forward stroke of the driven piston.

8. The combination with a motor actuated 115 driving piston, of a cylinder in which said piston works, provided with a by-pass at one end, permitting a fluid compressed at said end to pass to the opposite side of said driving piston when it is between the ends 120 of the by-pass, and an independent driven piston moved by the compressed fluid passing through the by-pass, the ends of said by-pass being spaced apart sufficiently to permit continuation of the compression stroke of the driving piston and discharge of the fluid medium until after the driven piston commences its opposite stroke.

9. The combination of suitably housed independently movable driving and driven 130

5   pistons, and means causing simultaneous movement during the retracting stroke of the driving piston but permitting independent movement of said pistons, during the opposite stroke of the driving piston.

10   10. The combination of suitably housed independently movable driving and driven pistons, and means causing simultaneous movement during the retracting stroke of the driving piston, but permitting independent movement of said pistons, during the opposite stroke of the driving piston, and said driving piston causing compression of an expansible medium during such simultaneous movement and said expansible medium being permitted to exert its expansive force against the driven piston during the independent movement.

15   11. The combination of suitably housed driving and driven pistons, said driving piston adapted to develop pressure in a fluid on one stroke, means delivering the fluid to drive the driven piston in the other direction, and means causing the pistons to travel 20 in the same direction on the pressure developing stroke.

20   12. In combination, a suitably housed driving piston compressing an expansible fluid on one stroke, means admitting air to 25 the compression side of said piston during its other stroke, a suitably housed independent piston, means causing said independent piston to be retracted on the compressing stroke of the driving piston, and means through which the independent piston receives its working stroke from the fluid compressed during such retraction.

25   13. In combination, a suitably housed driving piston compressing an expansible fluid, a suitably housed independent piston, means causing said independent piston to 30 be retracted on the compressing stroke of the driving piston, means through which the driven independent piston receives its working stroke from the fluid compressed during such retraction, and means permitting the escape of said fluid from the presence of the driven piston, after imparting the desired driving pressure thereto.

35   14. In a machine, a compressing piston, developing pressure in a fluid medium by one stroke of the piston, a working piston, a cylinder common to both of said pistons, and means for producing a vacuum chamber between the pistons to cause said compression piston to withdraw the working piston simultaneously with the compression of the expansible medium.

40   15. The combination of alined and suitably housed driving and driven pistons, the driving piston compressing a fluid on its rear face on one stroke, and means for delivering said compressed fluid between the opposed faces of the pistons.

45   16. The combination with alined driving

and driven pistons and a housing inclosing said pistons, of means for discharging a fluid compressed by the driving piston when the driving piston has reached a certain position, to cause the driven piston to be moved 70 in one direction independently of the driving piston.

50   17. The combination with a cylinder, of a pair of pistons movable therein, a motor for driving one of the pistons to compress a 75 fluid, and means for delivering said fluid between the pistons.

55   18. The combination with a driving piston, of a driven piston alined therewith, and a cylinder in which both pistons work, said 80 cylinder being provided with a by-pass and an inwardly seating valve near one end.

60   19. The combination of alined and suitably housed driving and driven pistons, the driving piston compressing fluid on its rear 85 face, on one stroke, means admitting a fluid to the rear face on the other stroke, and means for delivering the compressed fluid between the opposed faces.

65   20. The combination of the independently 90 movable and suitably housed driving and driven pistons, and mechanical means causing simultaneous movement during the retracting stroke of the machine but permitting independent movement of said pistons, 95 during the working stroke of the machine.

70   21. The combination of the independently movable and suitably housed driving and driven pistons, and mechanical means causing simultaneous movement during the retracting stroke of the driven piston but permitting independent movement of said pistons, 100 during the working stroke of the driven piston, said means being operated by the fluid pressure to permit the independent movement.

75   22. The combination with a motor actuated driving piston, of a cylinder in which the said piston works, provided with a by-pass at one end, permitting a fluid compressed at said end to pass to the opposite side of said driving piston when it is between the ends of the by-pass, and an independent driven piston moved by the compressed fluid passing from the by-pass and 110 mechanical means causing both pistons to move together in one direction.

80   23. The combination with a pair of alined and suitably housed pistons, of a motor driving one of the pistons to develop a fluid 115 pressure on one stroke of said piston, means delivering said fluid pressure to drive the other piston, and a mechanical means establishing a connection between the pistons on the pressure developing stroke.

85   24. The combination with a pair of alined and suitably housed pistons, of a motor driving one of the pistons to develop a fluid pressure on one stroke of the said piston, means delivering said fluid pressure to drive 120

125

130

the other piston, a mechanical means establishing a connection between the pistons on the pressure developing stroke, and fluid pressure operated means releasing said mechanical means when the fluid is delivered to operate the fluid pressure-operated piston.

25. The combination of alined and suitably housed driving and driven pistons, mechanical connection between the two pistons causing the pistons to move in the same direction at one time, automatic means for breaking said connection, and means storing an expansible fluid upon the movement 10 of the pistons in the same direction and causing said expansible fluid to drive the driven piston in the other direction.

26. The combination with a pair of alined and suitably housed pistons, of a motor driving one of the pistons to develop a fluid pressure on one stroke of the said piston, means delivering said fluid pressure to drive the other piston, dogs carried by one of said pistons to cause them to move together on the pressure developing stroke, and means 20 automatically releasing the dogs to permit the fluid driven pistons to move independently of the motor actuated piston.

27. The combination with a compression 30 piston, and a driven piston, of a common cylinder for the pistons embodying means for producing a vacuum chamber between said pistons to cause the compression piston to withdraw the driven piston simultaneously with compressing a fluid to drive the driven piston forward.

28. The combination with a compression piston and a driven piston, of a common cylinder for the pistons embodying means 40 for producing a vacuum chamber between said pistons to cause the compression piston to withdraw the driven piston simultaneously with compressing a fluid to drive the driven piston forward, and means whereby 45 fluid medium under pressure is delivered to the pressure driven piston near the end of the retraction of said pressure driven piston.

29. The combination with a cylinder, of a 50 pair of pistons working in the cylinder, a motor driving one of the pistons and developing a fluid pressure on one stroke of said piston, said cylinder embodying means for admitting fluid between the pistons to drive the driven piston, the cylinder forming a vacuum chamber between said pistons whereby the pressure developing stroke of the motor-actuated piston will cause a vacuum 55 between the pistons and return the fluid driven piston.

30. The combination with a cylinder, of a 60 pair of pistons working in the cylinder, a motor driving one of the pistons and developing a fluid pressure on one stroke of said piston, means admitting the compressed

fluid between the pistons to drive the other piston, means for displacing the fluid from between the pistons forming a vacuum, whereby, during the pressure developing stroke, the motor-actuated piston will retract the fluid driven piston, and means for assisting the vacuum to return the fluid driven piston.

31. The combination with a cylinder, of a pair of pistons working in the cylinder, a 70 motor driving one of the pistons and developing a fluid pressure on one stroke of said piston, means admitting the fluid between the pistons to drive the other piston, means for displacing the fluid from between the pistons forming a vacuum whereby, during the pressure-developing-stroke the motor-actuated piston will retract the fluid driven piston, and mechanical means establishing a connection between the pistons on 75 the pressure developing stroke.

32. The combination of a continuously running motor, a driving piston reciprocally actuated thereby, a cylinder in which said piston compresses a fluid medium on one 90 stroke, a driven piston also working in said cylinder, and retracted during the compression stroke of the motor actuated piston, means communicating the pressure medium to the driven piston for projecting the latter, and means permitting the escape of such pressure medium after imparting the desired work to the driven piston; the motor-actuated driving piston following the projection of the driven piston, driving out the 95 pressure medium from between the pistons and establishing retracting relation between the pistons.

33. The combination with a pair of pistons, a motor driving one of the pistons, a 105 cylinder in which the pistons work, formed to store a fluid upon one stroke of the motor actuated piston and to deliver said fluid between the pistons to drive the other piston in one direction, a valve permitting fluid to 110 enter the cylinder on one side of the motor actuated piston on the other stroke of the said piston, and a valve permitting an exhaust between the pistons during this latter stroke.

34. The combination with a cylinder, of a pair of pistons movable therein, a motor driving one of the pistons, the cylinder being provided with a by-pass near the end in which the motor driven piston works, the 120 ends of the by-pass being spaced apart to permit the piston to be positioned between them, means for admitting a fluid at the by-pass end of the cylinder, when the motor driven piston moves away from said end, 125 and means for exhausting the fluid between the pistons during such movement.

35. The combination of a suitably housed driving piston developing pressure in an 130 expansible fluid on one stroke, a suitably

housed driven piston, and means admitting the fluid compressed by the driving piston to the driven piston to drive the latter before the driving piston reaches the end of its compression stroke, and continuing said compression and admission until the driving piston reaches the end of its stroke.

36. The combination of a suitably housed driving piston developing pressure in an expansive fluid on one stroke, a suitably housed driven piston, and a by-pass having one end located to be uncovered by the driving piston before the latter reaches the end of its pressure developing stroke, and the other end located so that the piston continues to compress the fluid after the first mentioned end is uncovered.

37. The combination of a tool carrying member, a suitably housed reciprocating piston connected with the tool carrying member, and imparting thereto a percussion stroke and a retracting stroke, a second suitably housed reciprocating piston, communication between the respective pistons through which the second imparts movement to the first, the housing for the second named piston being provided with a ported passage toward its compression end adapted to be uncovered by one of said pistons whereby fluid pressure is developed during the retracting stroke of the first piston and permitted to act expansively against said first piston on its percussion stroke.

38. The combination of a tool carrying member, a suitably housed piston connected with the tool carrying member and imparting thereto a percussion stroke and a retracting stroke, a second suitably housed piston, fluid communication between the said pistons through which one imparts movement to the other, the housing for said pistons embodying a by-pass adapted to be uncovered by one of said pistons whereby fluid pressure is developed on the retracting stroke of the first piston and whereby said fluid pressure is exerted expansively against the piston of the tool carrying member, on its percussion stroke, and an electric motor driving the said second piston.

39. The combination with a reciprocating tool and a pair of suitably housed pistons, one of which is connected to the tool, of connection between the pistons whereby one imparts movement to the other during both the retracting and the percussion strokes of the tool, said movement imparting piston developing fluid pressure on the retracting stroke of the tool and means for utilizing said fluid pressure expansively to impart movement to the tool during the percussion stroke of the latter, and in addition to the driving effect of the second piston.

40. In a percussive tool or machine, the combination of a tool carrying member, a suitably housed reciprocating driven piston

connected with the tool carrying member, a suitably housed reciprocating driving piston imparting movement to the first named piston, in the direction of its percussion stroke and also in the direction of its retracting stroke, said driving piston causing fluid pressure to be developed on the retracting stroke of the tool and means whereby said fluid pressure is permitted to re-act expansively against the driven piston on its percussion stroke; means for displacing the fluid from between said pistons to form a vacuum, the action of the driving piston on the driven piston in the direction of its percussion stroke being through the medium of the body of fluid in which pressure is developed by the retracting stroke whereby the acceleration of the driven piston relatively to the driving piston does not remove it from the influence of the driving piston.

41. A percussion implement having a compressing cylinder, a piston therein, and an air-inlet communicating with the rear end of the cylinder and with the cylinder forward from its rear end, whereby the air is compressed by a backward stroke of the piston before entering the cylinder in front of the piston.

42. In a percussion implement, the combination of a compressing-cylinder having an air-inlet port a piston in said cylinder, an air passage communicating with the rear end of the cylinder and with the cylinder forward from its rear end, and an inwardly opening normally closed spring-held valve controlling the air-inlet port for said cylinder.

43. In a fluid-pressure-driven percussion tool, the combination of a suitably housed fluid pressure-driven tool-carrying piston a suitably housed motor-driven fluid-compressing piston and a by-pass leading from the compression side of the compressing piston to the tool carrying piston; said compression piston acting as a valve uncovering said by-pass after developing efficient compression in the fluid pressure medium.

44. The combination of a cylinder, a motor driven piston suitably housed therein and coöperating therewith to cause compression of a fluid, a fluid pressure driven piston also suitably housed in said cylinder and means for delivering the compressed fluid between the pistons to drive the fluid pressure driven piston in one direction.

45. The combination of a suitably housed piston, a motor driving said piston in each direction, a suitably housed fluid pressure driven piston, communication between opposed faces of the two pistons, the housing having a closed end for causing the motor driven piston to compress a fluid during one of its strokes and provided with a by-pass for delivering the fluid thus compressed to the space between the pistons whereby it

is permitted to act expansively to drive the pressure driven piston in one direction.

46. The combination of a motor driven piston, a fluid pressure driven piston, a suitable housing for both pistons, and a chamber in said housing between the opposed faces of the said pistons, said housing having a closed end for causing the motor driven piston to compress the fluid on one stroke, and provided with a by-pass for delivering the fluid into the chamber between the opposed faces of the pistons whereby said fluid is permitted to act expansibly to drive the pressure driven piston in one direction and means whereby the motor driven piston retracts the pressure driven piston during the compression stroke.

47. The combination with a pair of suitably housed pistons; of means causing both pistons to move in the same direction together and means for delivering a compressed fluid between the pistons to drive one of them independently of the other.

48. The combination with a cylinder containing driving and driven pistons, of means causing both pistons to move in the same direction during a retracting stroke and means delivering a compressed fluid between the pistons whereby the driven piston moves independently of the driving piston during the percussion stroke.

49. A percussion implement having a suitably housed compression piston adapted on one face to compress air for a subsequent pulsation of a tool, the housing for said piston embodying automatically controlled means for passing the compressed air to the opposite face of the piston.

50. A percussion implement having a suitably housed compressing piston adapted on one face to compress air for a subsequent pulsation of a tool, and means controlled by the piston for passing the compressed air to the opposite face of the piston.

45. 51. The combination of suitably housed driving and driven pistons having opposed faces, the driving piston compressing a fluid on its rear face on one stroke, and means for delivering said compressed fluid between the opposed faces of the pistons.

52. The combination with a cylinder, a pair of pistons movable therein, a motor for driving one of the pistons, of an inlet check valve located in the wall of said cylinder near the rear end and means for affording communication between the space included by the wall of the cylinder, the rear cylinder head and the rear face of the motor driven piston and the space included by the wall of the cylinder the forward face of the motor driven piston and the rear face of the forward piston.

53. The combination with a substantially air tight cylinder of two pistons in said cylinder, whereby it is divided into a cen-

tral and two end chambers, and an inlet check valve near one end of the cylinder adapted to admit air from the atmosphere.

54. In a fluid pressure-driven percussion tool, the combination of a fluid pressure driven tool-carrying piston, a motor-driven compression piston, a suitable housing for said pistons comprising a by-pass leading from the compression side of the compressing piston to the tool-carrying piston; one of said pistons acting as a valve for covering said by-pass while fluid pressure is being developed, and for uncovering said by-pass after efficient compression in the fluid pressure medium has been developed.

55. A percussion tool comprising an air-compressing driving piston, a driven piston, a suitable housing for said pistons, comprising a port communicating between the compressing space of the driving piston, and the pressure-receiving face of the driven piston; said port being opened after the driving piston has developed the air compression, whereby the pressure medium acts expansively against the driven piston.

56. A percussion tool comprising an air-compressing driving piston, a driven piston, a suitable housing for said pistons, comprising a passage communicating between the compressing space of the driving piston and the pressure-receiving face of the driven piston; said passage being opened by the movement of one of said pistons, after the driving piston has developed compression, whereby the pressure medium acts expansively against the driven piston.

57. A percussion machine comprising a suitable wheeled mounting, and the following instrumentalities combined in a single structure thereon and bodily movable to and from the work therewith, to wit:—a piston-driven, reciprocating percussion member, a suitable housing for said percussion member, a passage in said housing successively releasing compressed charges of fluid pressure-medium and delivering the same into the housing of and against the piston of said percussion member, whereby said pressure medium acts expansively to develop the percussion stroke of the percussion member, a compression chamber having a discharge passage controlled by said passage, a compressing piston alternately drawing into and compressing in said compression chamber, successive charges of fluid pressure medium, and an electric motor driving said compressing piston, and receiving energy from an external source.

58. A percussion machine comprising a suitable portable mounting and the following instrumentalities combined in a single structure thereon and bodily movable therewith, to wit:—a piston driven, reciprocating percussion member, a suitable housing for said percussion member, a passage in

5 said housing successively releasing compressed charges of fluid pressure-medium and delivering the same into the housing of and against the piston of said percussion member, whereby said medium acts expansively to develop the percussion stroke of the percussion member, a compression chamber, the discharge from which is controlled by said driving piston, and a suitably actuated compressing piston alternately drawing into and compressing in said compression chamber, successive charges of fluid pressure medium.

10 59. A percussion machine comprising a suitable portable mounting, and the following instrumentalities combined in a single structure thereon and bodily movable therewith, to wit:—a piston-driven, reciprocating percussion member, a suitable housing for said percussion member, a passage in said housing for successively releasing compressed charges of fluid pressure-medium and delivering the same into the housing of and against the piston of said percussion chamber, the discharge from which is controlled by the compressing piston, and a suitably actuated compressing piston alternately drawing into and compressing in said compression chamber, successive charges of fluid pressure medium; said passage leading from the compression chamber and having a port discharging into the housing of the percussion member piston and opened by the compression piston after compression has taken place.

15 60. A percussion machine comprising a suitable mounting, and the following instrumentalities combined in a single structure thereon, to wit:—a piston-driven, reciprocating percussion-member, a suitable housing for said percussion member, a passage in said housing for successively releasing compressed charges of fluid pressure-medium and delivering the same into the housing of and against the piston of said percussion member, whereby said pressure medium acts expansively to develop the percussion stroke of the percussion member, a compression chamber having its discharge controlled by the compressing means, auxiliary means comprising a valve supplying pressure-medium to said compression chamber, and suitably actuated means compressing in said compression chamber, successive charges of fluid pressure medium.

20 61. A percussion machine comprising a suitable mounting, and the following instrumentalities combined in a single structure thereon, to wit:—a piston-driven, reciprocating percussion-member a suitable housing for said percussion member, a passage in

25 pressed charges of fluid pressure-medium and delivering the same into the housing of and against the piston of said percussion member, whereby said percussion medium acts expansively to develop the percussion stroke of the percussion member, a compression chamber having its discharge controlled by the compressing means, auxiliary means comprising a valve supplying pressure-medium to said compression chamber, and suitably actuated means compressing in said compression chamber, successive charges of fluid pressure medium, and controlling said passage.

30 62. A fluid operated mechanism of the class described comprising a housing, and independently movable compressing and tool-operating elements arranged in alinement in said housing, said housing forming means for confining fluid until highly compressed by said compressing element and having a ported passage adapted to be periodically covered and uncovered by one of said elements for conducting the highly compressed fluid to the tool-operating element to drive the latter on its forward stroke at a speed greater than the corresponding movement of the compressing element.

35 63. A fluid-operated device of the class described comprising a regularly reciprocable fluid compressing element, a tool operating element reciprocable independently and at differential speeds relatively to the corresponding movements of the compressing element, and a casing for said elements having means for conducting compressed fluid from the compressing element to the tool operating element at a predetermined point in the stroke of the compressing element to drive the tool operating element at a speed greater than the regular movement of the compressing element, and also for producing a partial vacuum between said elements whereby the return stroke of the fluid compressing element will effect the return stroke of the tool operating element.

40 64. A fluid-operated device of the class described comprising a cylinder, a reciprocatory tool element and a fluid-compressing element both mounted in said cylinder, and means for introducing compressed fluid between the latter element and the tool operating element for driving the latter on its power stroke.

45 65. A fluid-operated device of the class described comprising a casing having a cylinder formed therein, independently reciprocable tool operating and fluid-compressing elements mounted in said cylinder, said cylinder and compressing element embodying means for compressing fluid at one side of the compressing element and said cylinder embodying means for introducing said compressed fluid between the opposite side of said compressing element and the tool oper-

ating element to drive the latter on its power stroke.

66. A machine of the class described comprising a suitable casing having a cylinder, tool operating and fluid-compressing pistons independently movable therein, the reciprocation of the compressing piston in one direction causing a compression of fluid at one side thereof, the casing being provided with 5 a by-pass for conducting the fluid thus compressed to a space between the opposite side of said compressing piston and the tool operating piston for driving the latter on its power stroke when the fluid compressing piston 10 reaches a predetermined position.

67. A machine of the class described comprising a suitable casing having a cylinder, tool operating and fluid compressing pistons independently reciprocable therein, the reciprocation of the compressing piston in one direction causing a compression of fluid at one side thereof, the casing being provided 20 with a by-pass having ports communicating with the cylinder at different points in its length for conducting the compressed fluid to a space between the opposite side of said compressing element and the tool operating piston.

68. In a pressure driven percussive tool, 30 the combination of a driving element, a tool carrying element, and a cylinder housing said driving element and said housing embodying means for introducing a body of highly com-

pressed air between opposed walls of said elements to drive the tool carrying element 35 upon its working stroke, and also having a closed end for causing the compression of a fluid to develop the tool driving pressure, upon the movement of the driving element in one direction.

69. In combination with driving and driven pistons, of a cylinder housing inclosing both of said pistons and having means providing communication between one face of the driven piston and both the compression and opposite faces of the driving piston through which fluid may pass alternately between the driving and the driven piston.

70. In a fluid pressure driven percussion tool, the combination of a suitably housed 50 pressure driven tool carrying piston, a suitably housed motor driven compressing piston, said housing comprising a by-pass leading from the compression side of the compressing piston to the tool carrying piston; 55 one of said pistons acting as a valve for covering said by-pass while pressure is being developed and for uncovering said by-pass after efficient compression in the fluid pressure medium has been developed.

The foregoing specification signed at Syracuse, N. Y., this 20th day of November, 1905.

ALEXANDER PALMROS.

In presence of two witnesses:

JOHN E. WOODRUFF,
JEREMIAH DRISCOLL.
